UNITED STATES PATENT OFFICE.

JOHN A. RUFFIN AND GEORGE G. GOING, OF NEW YORK, N. Y.

TYPE-WRITER.

1,063,289.

Specification of Letters Patent.

Patented June 3, 1913.

Application filed July 20, 1908. Serial No. 444,444.

To all whom it may concern:

Be it known that we, JOHN A. RUFFIN and GEORGE G. GOING, citizens of the United States, residing at New York, N. Y., have 5 invented certain new and useful Improvements in Type-Writers, of which the following is a specification.

Our invention relates to the general class of typewriters designed to print upon a sheet 10 held in flat form upon a flat platen, and one object of our invention is to provide a machine for visible writing and one capable of the interchange of type bars for printing in different languages or different styles of 15 type.

Our object also is to provide a machine in which the change from upper to lower case type or the reverse may be readily effected.

20 The invention consists in the features and combination and arrangement of parts hereinafter described and particularly pointed out in the claims.

In the accompanying drawings:—Figure 25 1 is a plan view of so much of a typewriting machine with our improvements embodied therein as will enable one skilled in the art to fully comprehend our invention; Fig. 2 is a side elevation of the machine embodying 30 our improvements; Fig. 3 is a central vertical sectional view from front to rear of the machine shown in Fig. 1; Figs. 4, 5 and 6 are detail views relating to the platen; Fig. 35 7 is a sectional view of ink ribbon mechanism; Fig. 8 is a plan view of a part of the machine to show the ink ribbon mechanism; Fig. 9 is a detail view of a part of escapement mechanism.

In these drawings, 1 indicates the main 40 base plate having ways at 2 for guiding a platen 3. This platen is in the form of a flat plate and is adapted to move from front to rear for line spacing. The printing mechanism is supported upon the base plate, for 45 which purpose said base plate is provided with standards 4 near the rear thereof which support a track or rail 5 extending transversely of the machine in an elevated position. A second track rail 6, parallel to the 50 rail 5, is arranged at the front of the machine in a position slightly above the platen, this rail being supported in short standards or ears 7 extending up from the base plate. The printing mechanism, including the keys 55 and key levers, is supported upon a carrier

plate 8 which, in turn, is supported upon the rails 5 and 6 by means of antifriction rollers 9—10 peripherally grooved to fit upon the cylindrical track bars 5 and 6. The rear roller 9 is journaled upon a pin extending 60 from a cross piece 12 of standard 11 secured to and extending upwardly from the rear portion of the carrier plate 8, while the front rollers, of which there are two, are carried in bearing plates or hangers 13 attached to the 65 carrier plate 8 at the front thereof. This plate 8, as above stated, carries the type bar mechanism, the key levers and other parts to be hereinafter described. The type bars, one of which is shown at 14, are pivoted at 70 15 by a wire or rod extending through the upturned portion 16 of the type bar carrying plate 17, this upturned portion being slotted, as shown in Fig. 1, to receive the type bars.

The type bar plate is provided with rearwardly extending arms 18 pivoted by a screw 19 passing through a slot 20 in each of the arms and into the uprights or standards 11. Each type bar is provided with a 80 notch at 21 receiving the pivot wire 15 and each is also provided at its lower end with a laterally projecting pin 22 in position overlying a projection or finger 23 on the key lever corresponding thereto. This key lever 85 is indicated at 24, pivotally supported on any suitable form of fulcrum 25 on the carrier plate 8, the said lever, at its front end, having any suitable form of key as at 26. Each type bar is under tension of a spring 90 27, there being one spring for each bar, and these bars extend upwardly from their pivot points. Each of the springs is connected with the type bar near its lower end at a point slightly above its pivot and the opposite end of the spring is connected to a supporting wire or rod 28 which is attached to a segmental part of the carrier frame. A segmental member 29 acts as a stop to hold the type bar in its elevated position, as 100 shown in Figs. 2 and 3. The effect of the spring is to hold the type bar normally elevated. When a key is depressed, the corresponding type bar will be swung on its pivot 25, the finger 23 of the key lever working 105 under the pin 22 of the type bar and the effect will be to throw the headed end of the type bar downwardly to cause the type carried thereby to make an impression upon the paper held flat upon the platen. Each type 110

- bar carries two type, one for upper and one for lower case, and these are arranged with their faces at an angle in respect to each other, so that, with the parts arranged as shown in full lines in Fig. 3, the operation of the key levers will cause the type bars to make impressions with the lower case type, the upper case type being at such an angle that they will not strike upon the paper on the platen. For printing with the upper case type, it is simply necessary to tilt the entire type bar carrying plate 17 for which purpose the said plate is pivotally supported, as at 19—20, in the manner above described.
- 15 The position assumed by the type bar plate and the type bars for printing with upper case characters is indicated in dotted lines in Fig. 3, and in order to adjust the type bar carrying plate with the type bars into this position, we provide a slidable frame composed of sides 30 which are made up of metal bars set up on edge and guided in their forward and backward movement in standards or lugs 31 secured to the carrier plate 8. There is one of these bars located at each side of the carrier plate 8, and they are connected by a cross bar 32. At their rear ends they are provided each with an inclined slot 33, Fig. 2, which receives a stud or pin 34 extending from the type bar plate at a point in front of the pivot thereof. The controlling or adjusting frame made up of the bars 30 may be moved toward the front of the machine in any suitable manner, and as one way of accomplishing this movement, we show a slot 35 at the front end of one of the bars 30, this slot being inclined and receiving a stud or pin 36 of a key standard 37, shown in dotted lines in Fig. 2, the upper end of said standard carrying a key 38. Upon the depression of this key, which has its standard suitably guided to have only vertical movement, the adjusting or controlling frame 30 will be drawn forwardly and the wall of the slot 33 in each of the bars 30 acting as a cam against the stud or screw 34 of the type bar carrying plate will tilt the said plate from the position shown in full lines for lower case printing to that shown in dotted lines for upper case printing. The movement of the controlling frame, in respect to the type bar carrying plate, is limited by a stop screw 39 passing through an ear 40 on the bar 30, a set nut 41 being provided to hold the stop screw in any position to which it may be adjusted, it being understood that one of these stop screws is used on each of the controlling or adjusting bars 30.
- 60 The effect of the forward movement of the controlling bars 30 is not only to tilt the type bar carrying plate upwardly, but also by means of the stop screw 39 to move it bodily in a forward direction so that the type carried by the type bar and correspond-

ing to the adjustment then made will strike accurately at the printing point. In order to allow this forward bodily movement of the type bar carrying plate, the pin and slot connection at 19—20 is provided as above described, and for the purpose of limiting the forward movement we provide on each of the pivot arms 18 an adjustable stop screw 42 passing through an ear 43 on the arm 18 and adapted to abut against the side of the screw or stud 19 and thus prevent further forward movement of the arm 18 and the type bar carrying plate to which said arm is connected. In order to operate the type bars for their printing strokes when in the elevated position indicated in dotted lines for upper case printing, each key lever is provided with an upper bearing edge at 44 and the act of adjusting the type bar carrying plate to the position shown in dotted lines in Fig. 3 will cause the pins 22 of the type bars to overlie the upper edge 44 of their respective key levers, so that, by operating these levers as above described, the corresponding type bars will be swung downwardly to make the impression. Each type bar is accurately guided to the printing point by means of a guide 45 consisting of an arm 46 attached to or formed with the type bar carrying plate, extending rearwardly therefrom and having, at its rear end, upwardly projecting divergent fingers to receive between them the type bars.

It will be observed that, while both the key levers and the type bars with the type bar carrying plate, is supported upon the carrier plate 8, the key levers are, in a measure arranged independently of the type bars and their carrying plate so that the latter may be adjusted into either of its positions without, in any way, affecting the position of the key levers. These remain in the same position for both adjustments of the type bar carrying plate, and their operation is identical in both instances, the effect of the adjustment of the type bar carrying plate being simply to move the type bars, with their pins 22, out of engagement with one portion of the lever and into engagement with another portion.

While we have described the normal position of the type bar carrying plate as being that shown in full lines, it will be understood that the type may be arranged for lower case printing while the type bar carrying plate is in the position shown in dotted lines; and it may be adjusted from this position to its lowermost position for printing with upper case, should this be desired. It will be further noticed that the point at which the type bars strike is always within view, whether the type bars are adjusted to one position or the other.

Should it be desired to change the machine as to the character of its type, the en-

tire type bar carrying plate, with its type bars, may be readily removed, and other carrying plates, with type bars having different characters or characters of a different language, may be readily placed in position and this may be done without affecting, in any way, the adjustment or position of the key levers and other parts of the machine. In order to effect this interchange of type 10 bar carrying plates, it will only be necessary to remove the studs or screws 19 and 34. The type bar carrying plate may rest by gravity in its lower position and if desired any suitable form of counterbalance may 15 be employed to, in a measure, counteract the weight of this plate, such, for instance, as the springs 47.

For letter spacing, we provide a rack bar 48 at the front of the machine extending 20 transversely thereof and engaged by a gear wheel 49 on a shaft 50 journaled, at its lower end, in the plate 8 and at its upper end upon a screw 51 held by a standard or supplemental frame 52 supported on the 25 carrier plate 8. This shaft carries loosely thereon an escapement wheel 53 having a spring pawl 54 attached thereto engaging a ratchet wheel 55 fixed on the shaft. The escapement wheel is under the control of a 30 pawl 56 and a detent 57, the latter being pivotally mounted between the screws 58 supported in the supplemental frame 52. The pawl is pivotally connected at 59 to the detent, and is under tension of a spring 60 35 connected, at one end, with the pawl and at the other end with the detent.

The carrier plate 8 is under tension of a spring in a drum 61 journaled in a bracket 62 connected to said carrier plate 8, the 40 drum having wound thereon one end of a tape or band 63, the opposite end of which is connected at 64 to the base plate, the tendency of this spring drum and band being to move the carrier plate 8 from left to 45 right for letter spacing. It is normally restrained against this movement by the detent, but upon rocking this detent on its pivot bearings 58, it will be removed from engagement with the escapement wheel and 50 said wheel will be allowed to move one step under the tension of the spring in the drum 61, until arrested by the pawl 56 which, by the same movement which releases the detent from the ratchet wheel, throws the pawl 55 into line therewith to be engaged thereby. The movement of the pawl is limited by a stop 65 so that, at each operation or pivotal movement of the detent, the carriage will be allowed to move one step toward the 60 right for letter spacing.

Any suitable form of universal frame may be employed, and as representative of any suitable construction for this purpose we show a bar at 66 arranged to overlie the 65 key levers to be operated thereby each time

one of said key levers is moved. This universal bar is suitably pivoted at 67 to the standards 31 by rearwardly extending arms 68 of said universal bar.

In order to release the carriage from its escapement, the rack bar 48 is arranged to be depressed for which purpose it is connected, at its ends, with supporting members or plates 69 suitably pivoted or hinged, as at 70, to the front standards 7. The rack bar is normally held up in position to engage the gear wheel 49 by means of a spring or springs 71, Fig. 2, suitably connected with the standard or ear 7 and bearing upon the under side of the rack bar. With this construction, in order to free the carrier plate from the rack bar, it is simply necessary to press said bar downwardly against the tension of the spring or springs 71 to disengage the said bar from the gear wheel 49, whereupon the plate 8, carrying the type bars and key levers, together with the escapement mechanism, may be moved freely in either direction, right or left. The stop segment or bar 29, to arrest the movement 90 of the type bars and hold them in substantially upright positions, and also the spring supporting rod 28, are conveniently carried upon upwardly extending arms 29* of the type bar carrying plate.

For line spacing we have provided means whereby the platen may be moved automatically in the act of returning the carriage of the printing mechanism toward the left from any position it may be occupying and also for operating the platen by hand independently of the carriage return lever. For this purpose the platen is provided with a rack 72 of any suitable form, that shown as an example consisting of a 100 plate or bar 72 of flat metal secured in the left hand edge of the platen and having a series of openings 73 therein to be engaged by a line space pawl 74 carried pivotally by a rod 75 extending from front to rear of the 105 base of the machine, its front end being pivotally connected to a line feed disengaging rod 76 which extends across the base and has downwardly turned ends pivoted at 77 to the sides thereof, a spring 78 being provided to hold this rod together with the pawl 74 and its rod 75 in retracted position. The pawl 74 works over a line feed regulator consisting of a plate or shield 79 fixed adjustably to the base by screws 80 passing 110 through slots 81 in the plate and into the base, a finger piece and set screw 82 being provided to adjust the shield or plate and to hold it in any position to which it may be desired to adjust it. By adjusting this 115 shield more or less of the movement of the pawl will be effective in moving the platen rearwardly for line spacing.

The platen, when moved for line spacing, is held by a detent 83. This engages the 120

openings 73 in the bar 72. It is operated to release the platen, when the line space feed thereof is to take place, by contact therewith of the end or a shoulder 84 of the line space rod. The detent may be either a pivoted one, as shown in Figs. 4 and 5, or it may be a vertically movable detent. In the former case it is pivoted to a stud 85 on the base and is pressed downwardly normally by a spring 86 so as to engage the rack bar or plate of the platen. It is provided with a guiding projection 87 for the line space rod, and its rear end, which is slightly tilted upwardly, is in position to be pressed upon by the under side of the line spacing bar, when this moves rearwardly for line spacing, so that the first effect of the rearward movement of the line spacing bar 75 is to press downwardly the tail end of the 10 detent so as to raise its front engaging end out of the opening in the platen rack bar to allow this, together with the platen, to move freely under the action of the line space pawl 74. The line space bar 75 is held 15 down to its work by a guiding projection 88 on the stud 85.

In order to allow the spring pressed detent to engage the rack bar of the platen as soon as the line spacing action has been 20 accomplished by the pawl 74, the rod 75 is cut away at 89 or is of other suitable form and arrangement to release the detent by freeing its tail end from pressure as soon as the rearward movement of the bar 75 25 has been completed. The released detent will therefore spring down immediately as soon as the cut away part of the rod 75 comes over its tail piece and the platen will then be retained against displacement.

As soon as the line feed disengaging rod 40 76 is released its spring restores it to normal position, thus moving the line space rod 45 forwardly and in this movement it does not disturb the detent for which purpose it is allowed slight lateral movement toward the left, there being sufficient free space under the guiding projection or lip 88 to permit this. This leftward movement of the bar 50 55 takes place as a result of its movement forwardly and the contact of its shoulder formed by the cut away part at 89 with the extreme end of the tail piece of the detent which, as shown in Fig. 1, is slightly inclined. The line feed bar will thus slip past the detent without disturbing it from its holding or pressed down condition and when the forward position of the bar is reached it will be pressed toward the right into normal position by its spring 91, this 60 right hand shifting movement being limited by the side of the rod striking against the stop in the detent. Instead of a pivoted 65 detent a vertically sliding detent 88*, Fig. 6, may be employed, this having the advantage that the platen will be held against

movement either forward or backward, which is also true of the pivoted detent.

The platen is adjustable in relation to its rack for which purpose the said rack is let into a groove in the side edge of the platen 70 where it is retained by pins 92 passing through slots 93 in the rack bar, as shown in dotted lines in Fig. 1. An adjusting screw 94 is arranged in the platen having finger pieces 95 at front and rear, by which 75 it may be turned, said screw engaging a lug 96 on the rack bar so that the platen may be adjusted in relation to the rack bar either forward or backward.

The line space bar may be operated by 80 hand for which purpose a push button is provided at 97 connected therewith or it may be operated, in a measure, automatically from the line feed lever. This line feed lever 98 is so arranged that it will 85 serve as a handle to return the carriage of the printing mechanism to the left for beginning a new line, and when grasped it will be given a movement to operate the line space mechanism, a part of said lever 90 contacting for this purpose with the rod 76 and having connection also with the carriage or letter spacing rack bar 48 to depress the same and thus release the carriage of the printing mechanism. This action can 95 be accomplished from any position of the carriage.

The platen is arranged to be taken out of its guides in the base and it may be reversed to present its under side uppermost. One 100 side or face of our platen is covered with comparatively soft rubber or other composition for ordinary work, and the other face is covered with hard rubber or other material for manifolding work. We thus provide, in 105 a single platen, interchangeability as regards the character of the printing surface and thus dispense with extra platens.

At 99 we provide a release device for the platen consisting of a finger lever pivoted to the side of the base and adapted, when swung on its pivot, to press the line feed disengaging rod rearwardly so as to release the detent from the platen rack, but yet not engage the pawl therewith. This 110 lever will hold the disengaging rod in the position to which it is moved and thus the platen will be perfectly free to be moved either forward or back by hand, or withdrawn and removed.

We indicate, in dotted lines at 78* in Fig. 3, a roller on a slide 79* supported in the base which, when adjusted to an extended position, will furnish a support for the platen when this is in its outward position. For convenience of illustration we have shown only one key lever and type bar, the arrangement of the others being a matter obvious to those skilled in the art.

We provide inking mechanism Figs. 7 and 13

8, in which a ribbon is employed, the arrangement being such that no reversing of the ribbon movement is necessary. At 100 the ribbon is shown as consisting of a continuous strip of fabric, the main portion of which is packed or folded within a box or receptacle 101 extending transversely of the base of the machine and beneath the platen. This box or storage chamber for 10 the ribbon has at one end (Fig. 7) a pair of rollers 102, 103, between which the ribbon passes into the box, and at the other end there is a single roller 104 over which the ribbon passes from the box to be thence 15 guided by a roller or other guide at 105 on the base and beneath the rearwardly extending arms of the carrier plate 8 at which point any suitable guiding devices, such as the wires or rolls 106, may be provided. 20 The ribbon then passes through a guide 107 arranged beneath the type bar guide above described. This guide 107 may consist of a spring member having an opening therein directly above the printing point over which 25 the inking ribbon is guided. At the left the ribbon is also guided over a roller or other guiding device 105. The shaft of the roll 102 has thereon an arm 108 carrying a pawl 109 which engages with a ratchet 30 wheel 110 arranged to turn loosely on the shaft of the said wheel 102, said ratchet wheel being formed with or connected to a gear wheel 111 with which meshes a rack bar 112 connected to the carrier plate 8 of 35 the printing mechanism. It will be seen from this that when the carrier plate 8 is moved step by step toward the right, it will traverse the inking ribbon and make the impressions by the type bars striking down 40 thereupon. In this movement to the right the rack bar 112 does not operate the ribbon rolls, as, on this movement, the ratchet wheel turns freely past the pawl carried by the fixed arm 108, but on the leftward movement of the carrier 8 to begin a new line, 45 the rack bar will, by operating the gear 111, cause the ratchet thereof to engage the pawl 109 and revolve the same about the axis of the roll 102, and thus through the said arm 50 108 revolve the said roll so that it will feed the ribbon into the box or receptacle 101 and in this feeding movement the ribbon will automatically fold itself substantially as shown in Fig. 7, and the layers, being 55 packed closely together, a large number of yards of ribbon may be used in the machine, and as it is fed into the box at one end and supplied to the machine by feeding it out from the box at the other end, the movement 60 is continuously in one direction and no reversing of the ribbon is necessary. It will be further observed that the amount of ribbon fed at each movement of the carrier plate toward the left will correspond exactly 65 with the number of letter impressions that

have been made during the time that the carrier plate 8 has been moving toward the right, and in this way uniformity of ink supply will be assured. This is not true, however, in those forms of inking mechanism in which the inking ribbon is wound upon a drum or roller, the passage of the ribbon to the printing point being faster at some times than at others. The rack bar 112 may be arranged in any suitable way to 70 fold in relation to the other parts of the machine, and for this purpose it may be pivoted as indicated at 113, but this is representative of any suitable way of providing an adjustable rack bar which may be folded 75 or adjusted for compactness when the machine is not in use.

We claim:

1. In combination in a typewriter, a plurality of upwardly standing type bars, each 85 carrying a plurality of type at different angles, said bars being arranged to strike downwardly and rearwardly, a support for the type bars pivotally supported at its rear portion, means for tipping up the front of 90 said support and means for sliding the support forwardly to bring another case type into play from that when the support is in its lowest position, and key levers for operating the type bars in either position, substantially as described.
2. In combination in a typewriter, a platen, a plurality of type bars, a segmental plate in which said type bars are pivotally mounted, said plate having its ends directed 100 rearwardly, said bars being arranged to strike downwardly and rearwardly upon a visible printing point, and key levers for operating the type bars, said type bar frame being pivoted at the rearwardly directed 105 ends of its arms and means for adjusting said frame, substantially as described.
3. In combination in a typewriter, a plurality of type bars, carrying a plurality of type in different angular positions, a support for said type bars with means for adjusting the same to bring either set of type into play, and key levers having each a plurality of engaging points to operate the type bars, said type bars being positioned 110 in appropriate relation to either one or the other of said bearing points by the adjustment of said support.
4. In combination in a typewriter, a platen, a series of key levers, a plurality of 115 type bars carrying each a plurality of type at angles to each other, and a support for said type bars adjustable upwardly and longitudinally in relation to said key levers to throw said type bars into connection with 120 different portions of key levers, substantially as described.
5. In combination in a typewriter frame, a platen, a series of key levers, type bars 125 each having a plurality of type in different 130

angular positions in respect to each other, a pivotally and slidably mounted support for said type bars, said support having a pin and slot connection with the frame, and 5 means for adjusting said support upwardly and longitudinally in respect to the key levers, substantially as described.

6. In combination in a typewriter, a platen, a series of key levers, type bars each 10 having a plurality of type in different angular positions in respect to each other, a pivotally and slidably mounted support for said type bars, and means for adjusting said support upwardly and longitudinally in respect to the key levers, said means comprising the sliding bars having a pin and inclined slot connection with the said support, substantially as described. 15

7. In a typewriter the combination of a platen, a series of key levers, a plurality of type bars each having thereon a plurality of type disposed angularly in respect to each other, a segmental frame carrying said type bars and means for adjusting said frame in 25 respect to the key levers, said frame being removable bodily with the type bars and interchangeable with frames carrying type bars with type of different style or language, the said keys having only contact 30 connection with the type bars and said connection being broken simultaneously as to all the type bars in the act of removing the frame, substantially as described.

8. In combination in a typewriter, a platen, a plurality of type bars having each 35 a plurality of type disposed angularly in respect to each other, an adjustable support for said type bars, key levers having two contact surfaces to engage the type bars in 40 each position of the adjustable support, and a guide for the type bars carried by the adjustable support and movable therewith.

9. In combination in a typewriter, type bars, key levers for operating the type bars 45 by contact therewith, a frame in which the type bars are pivoted, said frame being pivotally and slidably mounted, and a single

connection for tilting the said frame and sliding the same, substantially as described.

10. In combination in a typewriter, a series of type bars, a frame pivotally mounted and carrying said type bars, said frame being 50 slideable in a direct line toward the front and rear of the machine, and key levers for operating the type bars, substantially as described. 55

11. In combination in a typewriter, a series of type bars arranged to strike down upon the platen, a frame carrying the said type bars and pivotally mounted, said frame 60 also having sliding movement to adjust the type bars for upper and lower case printing, and key levers for operating the type bars, said frame being removable as one body, together with the type bars, and without disturbing the key lever connections, substantially 65 as described.

12. In combination in a typewriter, a series of type bars, a frame pivotally mounted at its rear end, a series of key levers, and 70 means for first lifting the front end of the type bar frame and then sliding the same bodily forward to change its adjustment in relation to the key levers, substantially as described. 75

13. In combination in a typewriter a series of key levers, a series of type bars, carrying each a plurality of type and a frame adjustable as one body to bring either type into play, said frame being also removable 80 as one body to change the character of the printing, said adjustment and removal of the frame taking place without affecting the key lever connections in relation to the said frame and type bars, substantially as described. 85

In testimony whereof, we affix our signatures in presence of two witnesses.

JOHN A. RUFFIN.
